LOAD HOOK CONNECTION

Charles S. Schroeder, Philadelphia, Pa., assignor
to The Yale & Towne Manufacturing Company,
Stamford, Conn., a corporation of Connecticut

Application August 25, 1944, Serial No. 551,126

5 Claims. (Cl. 59—95)

1

This invention relates to a chain hoist of the type disclosed in my Patents Nos. 2,335,571 and 2,342,091. In chain hoists of the class described the chain utilized is of the sprocket actuated type in which the links are pivoted to one another about a series of parallel pivots. Therefore, the chain is flexible in one plane only.

I have found that chain of the particular type is susceptible to breakage when associated in a conventional manner with a clevis and hook block. Thus, it is common in the prior art to mount the hook block for pivotal movement relatively to the clevis and then mount the yokes of the clevis for pivotal movement relatively to a clevis support, with the clevis support being itself pivoted to the last of the chain links on an axis parallel to the parallel pivots of the chain links. Because the yokes of the clevis are pivotally mounted relatively to the clevis support about an axis very close to the axis on which the clevis support is pivoted to the last chain link, but at right angles thereto, it becomes possible to move the hook and hook block together with the yokes of the clevis in such a manner as to kink the links of the chain, placing them in an unnatural position. As a matter of fact, through this positioning of the chain links the effective length of the chain is also decreased.

It then sometimes occurs that when a heavy load is assumed by the chain through the hook and hook block, the chain will not bear up under the load because of its unnatural position. In addition, because the effective length of the chain is decreased, it will strike the hoist as it moves upwardly so as to damage the hoist. This is, of course, made possible because the limit mechanism does not function effectively with the chain in its unnatural position.

It is the object of my invention to provide means whereby it will be impossible to place the chain in the unnatural kinked position that has been found so objectionable by the industry. I have found, after considerable and lengthy study, that if the hook block and clevis are not allowed to pivot sharply relatively to the lowermost chain link, as is possible in present structures, no kinking may occur. I, therefore, arrange for the securing of the clevis and its support to the chain through the intermediary of pitch chain links.

I have thus set forth my invention generally in order that those skilled in the art may better appreciate the relation of the invention to the prior art, and the contribution made thereby. While also I have indicated the operative theory

2

of my invention, it should be understood that I may not be entirely correct in that theory and that my invention should not be limited thereby.

Referring now to the drawings, Fig. 1 is a perspective view of a chain hoist of the type to which my invention is applied, the particular hoist being well illustrated and described in my patents supra.

Fig. 2 is an enlarged view of certain of the parts of Fig. 1.

Fig. 3 is a view taken at right angles of Fig. 2.

Referring now to the drawings, the hoist to which my invention is applied is designated by reference numeral 10 while the chain used in connection therewith is designated by reference numeral 11. This chain is formed of a series of links 12 pivoted to one another by parallel shafts 13 so as to be flexible in one plane only. Chain of the particular type is adapted for actuation by a sprocket mounted within the chain hoist 10, all as will be found apparent upon reference to applicant's earlier patents above referred to.

For handling a load, chains of the type indicated are adapted to support a clevis 14 relatively to which is pivoted a hook block 15 carrying a hook 16. The clevis 14 is formed with a pair of yokes 17 that in the prior art are pivoted to a yoke support that is in turn pivoted to the last link 12 of the chain 11. As is well set forth in an application of mine filed on even date herewith, Serial No. 551,127, it is possible to so maneuver the hook block 15 and hook 16 that the chain links will be placed in an unnatural kinked position. In the said application this unnatural position is illustrated, but is not herein shown because it is felt unnecessary to indicate the particular position in both applications.

In order to prevent the movement of the chain by the hook block 15 into the unnatural kinked position in which it is made extremely vulnerable to breakage, I use the type of connection illustrated in the drawings of this application. Thus, the yokes 17 of the clevis 14 are secured to a pitch chain link 18 by means of a bolt 19 and a nut 20 traversing aligned bores 21 in the yokes 17. The pitch link 18 is in engagement with a second pitch chain link 22 that in turn is engaged with a third pitch chain link 23. The link 23 is secured to the ear 24 of a fastener element 25 that is pivoted at 26 to the lowermost link 12 of chain 11 about an axis parallel to the pivot shafts of the chain 11. Because of this arrangement of the parts it is impossible to move the clevis 14 sharply and directly relatively to the lowermost link 12 and it is therefore impossible to maneuver the

parts into the very vulnerable objectionable position to which I have already alluded.

It is, therefore, seen that by a simple and very inexpensive change of the standard parts of the load block securing means of the prior art, I am able to obtain a result that has been sought eagerly for many years. I believe that the nature and operation of my invention will now be apparent.

I now claim:

1. In a combination of the class described, a sprocket roller load chain of the type having links that are pivoted to one another about parallel pivots so that said chain is substantially flexible in one plane only, a hook block assembly, and pitch chain links secured between said hook block assembly and said roller chain for attaching said hook block assembly to said roller chain.

2. In a combination of the class described, a sprocket roller load chain of the type having links that are pivoted to one another about parallel pivots so that said chain is substantially flexible in one plane only, a hook block, a clevis pivotally supporting said hook block, and pitch chain links secured between said clevis and said roller chain for attaching said clevis to said roller chain.

3. In a combination of the class described, a sprocket roller load chain of the type having links that are pivoted to one another about parallel pivots so that said chain is substantially flexible in one plane only, a hook block assembly, a plurality of assembled pitch chain links having the link at one end secured to said load block

assembly, and the link at the other end secured to said roller chain for attaching said hook block assembly to said roller chain.

5. In a combination of the class described, a sprocket roller load chain of the type having links that are pivoted to one another about parallel pivots so that said chain is substantially flexible in one plane only, a hook block assembly, a pitch chain link, means pivotally securing said pitch chain link to the lowermost link of said roller chain, a second pitch chain link secured below and relatively to said first pitch link, and means securing said second pitch chain link to said hook block.

10 15 20 25 5. In a combination of the class described, a sprocket roller load chain of the type having links that are pivoted to one another about parallel pivots so that said chain is substantially flexible in one plane only, a hook block assembly, a pitch chain link, means pivotally securing said pitch chain link to the lowermost link of said roller chain, a second pitch chain link secured below and relatively to said first pitch link, and a third pitch link securing said second pitch chain link to said hook block.
